UNITED STATES PATENT OFFICE.

FRED W. SPACKE, DALMAR T. BROWNLEE, AND WILLIAM SPACKE, OF INDIANAPOLIS, INDIANA, ASSIGNORS TO THE F. W. SPACKE MACHINE COMPANY, OF INDIANAPOLIS, INDIANA, A CORPORATION OF INDIANA.

INTERNAL-COMBUSTION ENGINE.

1,102,700.

Specification of Letters Patent. Patented July 7, 1914.

Application filed January 13, 1913. Serial No. 741 719.

To all whom it may concern:

Be it known that we, FRED W. SPACKE, DALMAR T. BROWNLEE, and WILLIAM SPACKE, citizens of the United States, residing at 5 Indianapolis, in the county of Marion and State of Indiana, have invented a new and useful Internal-Combustion Engine, of which the following is a specification.

Our invention relates to internal combustion engines, especially for motor cycles, and has for its object the provision of a multi-cylinder engine which combines a maximum of strength with a minimum of weight and space and operates with a minimum of friction. 15

The accompanying drawings illustrate our invention.

Figure 1 is an end elevation, with some parts broken away or in section, of a twin-cylinder internal combustion engine embodying our invention; Fig. 2 is a longitudinal section through the left hand cylinder of Fig. 1, the parts being shown in different relative positions; Fig. 3 is an enlarged elevation of a fragment of the cam shaft and associated parts; Fig. 4 is a plan view of the parts shown in Fig. 3; Fig. 5 is a longitudinal sectional view showing the mounting of the crank end of the pitman of the right hand cylinder of Fig. 1; and Fig. 6 is a fragmentary side elevation of one of the fly wheels, showing how it serves as a nut-lock. 20

Two cylinders 10 and 11 are set at an angle to each other on the top of a crank case 12. 25 The crank case has a removable end cover 13, held by bolts 14 to the crank case and meeting the latter on a joint which does not intersect the joint between the crank case and the cylinders. The crank case 12 and its cover 13 carry ball bearings 15 and 16, in which is mounted the engine crank shaft. This crank shaft has two stub shaft portions 17 and 18, provided at their respective adjacent ends with spaced disks 19 and 20 having eccentric projections 21 and 22 on their adjacent faces. These projections are cylindrical exteriorly and together form a support for a roller bearing 23 on which is mounted the crank end of a pitman 24, the other end of which is connected to a piston 25 in the cylinder 10. The projections 21 and 22 are bored out so that they are tapered interiorly, the large ends being toward each other or

at the adjacent ends of the projections. Within the projections is mounted a doubly 55 tapered bolt 26, screw-threaded at both ends to receive nuts 27 whereby the projections 21 and 22 may be clamped together on the bolt 26 and the disks 19 and 20 and their stub shafts 17 and 18 all will be held in proper 60 relative positions. Suitably mounted on the disks 19 and 20 are two fly-wheel disks 29, which are held against rotation by dowel disks 29' and are provided with suitably notched perforations 30 which fit loosely over 65 the nuts 27 and act as nut-locks therefor.

The pitman 24 is provided near its crank shaft end with a projection 31, offset from the body of the pitman in the plane in which the pitman operates and on the side toward 70 the cylinder 11. Straddling this projection 31 is the forked lower end 32 of the pitman 33 of the cylinder 11. A sleeve 34 extends through the projection 31 and the two prongs of the forked pitman end 32, conveniently fitting closely within the openings provided in the ends 32 but being spaced from the projection 31 by a wearing washer 35. The ends of the sleeve 34 and the adjacent parts of the two prongs of the forked 80 pitman end 32 are notched to receive fingers 36 of cap-plugs 37 set in the ends of the sleeve, thereby locking the sleeve and the pitman end 32 together. The cap-plugs 37 are held in place by a rivet rod 38 connecting them. The projection 31 is so located that the center line of the pitman 33 always extends approximately through the axis of the bolt 26. By mounting but one of the pitmen directly on the crank shaft and the 90 other on the first, the strength of the whole is greatly increased and larger bearings can be provided for the one mounted on the crank shaft. These advantages more than compensate for the slight displacement at 95 certain times between the center line of the pitman 33 and the center of the bolt 26. As there is but a comparatively slow and small oscillation between the pitman 33 and the projection 31, roller bearings between such 100 parts are not needed.

On the end of the crank shaft is mounted a suitable pulley 40, by which power is transmitted to the mechanism to be driven, such as the driving wheel of a motor cycle. 105 On the end 18 of the crank shaft is mounted

a spiral gear 41, which meshes with a spiral gear 42 on a cam shaft 43 mounted in the cover 13, the gears ordinarily producing a cam shaft speed equal to one half the crank shaft speed. This cam shaft 43 is inserted endwise into place, from the right hand side as seen in Fig. 1, its left hand end extending into a bearing bushing 44 suitably mounted in the cover 13 and its right hand end being supported in and projecting through a removable bearing 45 which is inserted in place with the cam shaft and clamped thereby by bolts 46. Thrust bearings 47 are located between the two ends of the bearing 45 and collars 48 and 49 on the cam shaft 43, to prevent endwise movement of the latter with a minimum of friction. The collar 49 is removable, to allow the assembling and dismantling of the cam shaft 43 and bearing 45, being clamped in place by a nut 50 which also adjustably clamps a spiral gear 51 on the cam shaft 43. The spiral gear 51 meshes with a spiral gear 52 on the shaft 53 of a magneto 54. The collar 48 also forms one of a series of cams 48, 55, 56, and 57 on the cam shaft 43. The operating faces of these cams are all toward the spiral gear 42. These cams coöperate with bell-crank levers 58, 59, 60, and 61 respectively, which bear against the lower ends of and operate the valve-operating rods 62, 63, 64 and 65 for the exhaust valve of the cylinder 11, the inlet valve of the cylinder 11, the inlet valve 66 of the cylinder 10, and the exhaust valve 67 of the cylinder 10. The four bell-crank levers are mounted on a frame 68 suitably held by bolts 69' to the inside of the cover 13, ends of pivot pins for the bell-crank levers fitting in suitable holes 69 in the cover 13. The four cams are so located relatively to each other, and the gears 41 and 42 are in such ratio, that the valve-operating rods 62, 63, 65, and 64 are operated in the proper sequence to admit fuel to the two cylinders and allow the burnt gases to exhaust therefrom at the proper times. The bell-crank levers 58 and 61 are provided with additional arms 70 and 71 respectively, which arms project upward into the path of slidable rods 72 and 73 respectively. These rods are spring-pressed toward each other by springs 74 and 75, and their adjacent ends bear against a double cam 76 on a vertical shaft 77 provided with an operating arm 78, which may be suitably connected to any desired control point. By turning the shaft 77 in a counter-clockwise direction (Fig. 4), the rods 72 and 73 are forced apart and the bell-crank levers 58 and 61 tilted to raise the valve-operating rods 62 and 65 to open the exhaust valves. This allows the engine to be started rotating easily, as by pedaling, without the resistance which would otherwise be offered by the compression of whatever gases happened to

be contained within the cylinders 10 and 11, thus materially facilitating starting. After the engine has been given sufficient momentum, the exhaust valves are allowed to close, whereupon the engine will begin to operate under its own power.

We claim as our invention:

1. In an internal combustion engine, the combination of cylinders, inlet and exhaust valves therefor, and a cam shaft for operating said valves, said cam shaft having a separate cam for each valve, the cam faces of the cams acting axially of the cam shaft and part in one direction and part in the other. 75

2. In an internal combustion engine, the combination of inlet and exhaust valves, a cam shaft for operating said valves, said cam shaft having a separate cam for each valve, the cams having cam faces on the sides, said cam faces facing part toward one end of the axis of the cam shaft and part toward the other end thereof. 85

3. In an internal combustion engine, the combination of inlet and exhaust valves, 90 valve-operating rods, bell-crank levers for operating said rods, and a cam shaft having cams for operating said bell-crank levers, said bell-crank levers bearing against the sides of the cams part in one direction and part in the other axially of the shaft, and said cams having cam faces on the sides against which said bell-crank levers bear. 95

4. In an internal combustion engine, the combination of inlet and exhaust valves, 100 valve-operating rods, bell-crank levers for operating said rods, and a cam shaft having cams for operating said bell-crank levers, said bell-crank levers bearing against the sides of the cams, and said cams having cam 105 faces on the sides against which said bell-crank levers bear.

5. In an internal combustion engine, the combination of a plurality of cylinders, inlet and exhaust valves therefor, valve-operating 110 rods, bell-crank levers for operating said rods, a cam shaft having cams for operating said bell-crank levers, said bell-crank levers bearing against the sides of the associated cams part in one direction and part in the 115 other, and said cams having cam faces on the sides, against which cam faces the associated bell-crank levers bear, and unitary means for operating the bell-crank levers for the exhaust valves of a plurality of cylinders 120 to open such valves independently of the cam shaft.

6. In an internal combustion engine, the combination of a plurality of cylinders, inlet and exhaust valves therefor, valve-operating 125 rods, bell-crank levers for operating said rods, a cam shaft having cams for operating said bell-crank levers, said bell-crank levers bearing against the sides of the associated cams, and said cams having cam faces on the 130

5 sides, against which cam faces the associated bell-crank levers bear, and unitary means for operating the bell-crank levers for the exhaust valves of a plurality of cylinders to open such valves independently of the cam shaft.

7. In an internal combustion engine, the combination of a plurality of cylinders, inlet and exhaust valves therefor, valve-operating rods, bell-crank levers for operating said rods, a cam shaft having cams for operating said bell-crank levers, and unitary means for operating the bell-crank levers for the exhaust valves of a plurality of cylinders to open such valves independently of the cam shaft.

8. In an internal combustion engine, the combination of a plurality of cylinders, inlet and exhaust valves therefor, valve-operating rods, bell-crank levers for operating said rods, a cam shaft having cams for operating said bell-crank levers, and unitary means for operating the bell-crank levers for the exhaust valves of a plurality of cylinders to open such valves independently of the cam shaft, said last-named means comprising a cam having a plurality of cam faces and sliding rods extending from said last named cam to projections on the bell-crank levers for the exhaust valves.

9. In an internal combustion engine, the combination of a crank shaft, a crank case provided with a cover through which said crank shaft extends, a cam shaft, and a pair of bearings for said cam shaft, said bearings being mounted in the cover of the crank case.

10. In an internal combustion engine, the combination of a crank shaft, a crank case, a cam shaft extending transversely of the crank shaft, and a pair of bearings for said cam shaft, said bearings being mounted in the crank case.

11. In an internal combustion engine, the combination of a crank shaft, a crank case, a cam shaft extending transversely of the crank shaft, a pair of bearings for said cam shaft, said bearings being mounted in the crank case, and thrust bearings for preventing endwise movement of such cam shaft, said thrust bearings acting against opposite sides of one of the cam shaft bearings.

12. In an internal combustion engine, the combination of a crank shaft, a crank case, a cam shaft extending transversely of the crank shaft, and a pair of bearings for said cam shaft, said bearings being mounted in the crank case, one of said bearings being removably mounted in said case so that it and the cam shaft can be removed as a unit axially of the cam shaft.

13. In an internal combustion engine, the combination of a crank casing, a removable cover therefor, a cam shaft carried by said

cover and removable therewith and separable therefrom, a frame carried by and removable from said cover, a plurality of levers carried by said frame and operated by the cams on the cam shaft, and valves operated by said levers.

14. In an internal combustion engine, the combination of a crank casing, a removable cover therefor, a cam shaft carried by said cover and removable therewith, a frame carried by and removable from said cover, a plurality of levers carried by said frame and operated by the cams on the cam shaft, and valves operated by said levers.

15. In an internal combustion engine, the combination of a crank casing, a removable cover therefor, a cam shaft carried by said cover and removable therewith and separable therefrom, a frame carried by said cover, a plurality of levers carried by said frame and operated by the cams on the cam shaft, and valves operated by said levers.

16. In an internal combustion engine, the combination of a crank casing, a removable cover therefor, a cam shaft carried by said cover and removable therewith, a frame carried by said cover, a plurality of levers carried by said frame and operated by the cams on the cam shaft, and valves operated by said levers.

17. In an internal combustion engine, the combination of a cam shaft, cams thereon having axially acting operating faces, a plurality of valve-operating levers having their axes transverse to the axis of the cam shaft but in a line substantially parallel to the cam shaft, and valves operated by said levers.

18. In an internal combustion engine, the combination of a casing, a frame carried by said casing but removable therefrom, a plurality of valve-operating levers carried by said frame, a cam shaft provided with cams for operating said valve-operating levers, and valves operated by said levers.

19. In an internal combustion engine, the combination of a crank case provided with a cover, a crank shaft mounted in said case and extending through said cover, a cam shaft extending transversely to said crank shaft, and a pair of bearings for said cam shaft, said bearings being mounted in the cover of the crank case, and one of said bearings and said cam shaft being together removable axially from said cover.

20. In an internal combustion engine, the combination of a crank case provided with a cover, a crank shaft mounted in said case and extending through said cover, a cam shaft extending transversely to said crank shaft, a pair of bearings for said cam shaft, said bearings being mounted in the cover of the crank case, and one of said bearings and said cam shaft being together removable

axially from said cover, and thrust bearings for preventing relative endwise movement between said cam shaft and said removable bearing, said thrust bearings acting against opposite sides of said removable bearing.

21. In an internal combustion engine, the combination of a crank casing, a removable cover thereon, a crank shaft carried by said casing and cover and having a bearing in the latter, a cam shaft carried by said cover and removable therewith, a frame carried by and removable from said cover, a plurality of levers carried by said frame and

operated by cams on the cam shaft, and valves operated by said levers.

In witness whereof, we have hereunto set our hands at Indianapolis, Indiana, this tenth day of January, A. D. one thousand nine hundred and thirteen.
